(57) **CLAIM**

We claim the ornamental design for the windshield-mounted punch bag as shown and described.

DESCRIPTION

The present design relates to a windshield-mountable punch bag where such installation is positionally stable, rigid and non-obtrusive to a driver's vision. The device of the present design removably attaches to the upper inner central portion of a windshield using suction-type cup fasteners. Additionally, the lower portion of the device is detachable and can incorporate the insertion of a plurality of ornamental or functional devices.

FIG. 1 is a top perspective view of the windshield-mounted punch bag showing our new design installed on a windshield;

FIG. 2 is a left side elevation view thereof.

FIG. 3 is a right side elevation view thereof.

FIG. 4 is a front elevation view thereof; and,

FIG. 5 is a bottom plan view thereof.

The dotted lines in the drawing figures are for illustrative purposes only and do not form part of the claimed design.
